UNITED STATES PATENT OFFICE

2,555,140

PATTERN CONTROL FOR KNITTING MACHINES

Walter Larkin, Norristown, Pa., assignor to
Fidelity Machine Company, Inc., Philadelphia,
Pa., a corporation of Pennsylvania

Application June 30, 1949, Serial No. 102,396

10 Claims. (Cl. 66—135)

1

This invention relates to improvements in multidesign rib knitting machines of the character disclosed in United States Patent No. 2,051,724.

One object of the invention is to materially increase the permissible operating speed of the machine with resulting improved production characteristics.

Another object, contributing to the improved production characteristics, is to materially improve the precision with which the machine operates, particularly in those parts which control the operation of the mechanism producing the vertical stripes.

Still another object is to materially increase the flexibility and versatility of the machine in the formation of the interknit ornamental designs which the machine is capable of producing.

A still further object is to increase the capacity of the control mechanism so that the machine may be set for a plurality of different selective designs.

The invention contemplates also provision of a control mechanism of simplified and generally improved character as hereinafter described and illustrated in the attached drawings, wherein:

Fig. 1 is a fragmentary side elevational view of a knitting machine having control mechanism made in accordance with the invention;

Fig. 2 is a sectional view on the line 2—2, Fig. 1;

Fig. 3 is a fragmentary sectional view showing a detail of the control mechanism;

Fig. 4 is a sectional view on the line 4—4, Fig. 2;

Fig. 5 is a fragmentary perspective view showing another detail of the improved control mechanism;

Fig. 6 is a sectional view on the line 6—6, Fig. 4;

Fig. 7 is a fragmentary perspective view showing still another detail of the control mechanism;

Fig. 8 is a fragmentary perspective view showing a still further mechanical detail;

Fig. 9 is an enlarged fragmentary sectional view of the needle wrapping mechanism of the machine and of the associated control elements;

Fig. 10 is a section on the line 10—10, Fig. 9; and

Fig. 11 is a face view of a fragment of knitted fabric illustrating the nature of the designs that may be produced on the machine.

With certain exceptions, hereinafter described, the machine shown in the drawings is essentially the same as that disclosed in the aforesaid United States Patent No. 2,051,724. With reference particularly to Figs. 1 and 2, the bed plate of the

machine is indicated by the reference numeral 1; 2 is the cylinder cam plate mounted for rotation in a circular opening in the bed plate; and 3 is the conventional split cylinder cam ring attached to the cam plate 2. A base ring 4, mounted on the base 5, supports the plate 2 and has attached thereto the cylinder supporting ring 6. The stationary needle cylinder 7 is attached to and extends upwardly from the ring 6, said cylinder receiving the cylinder needles 8 in conventional manner. These needles are actuated by the rotary cam 9 within the ring 3.

Dial plate 11, attached to the lower end of stationary dial post 12, receives the dial needles 13 in conventional manner, these needles being actuated by dial cam 14 on the rotary dial cam plate 15. The plate 15 is secured to the lower end of tubular shaft 16, said shaft depending from a bevel gear 17 attached to upper end of the shaft and journaled in the stationary superstructure 18.

A hollow stationary column 19, connected at its upper end to the superstructure 18, has attached to its lower end a cylindrical needle wrapping finger carrier 21. As shown in Fig. 4, this carrier is provided with a circumferential series of narrow radial slots 22 the function of which will be hereinafter set forth. Threaded onto the upper end of the carrier and embracing the upper ends of the slots 22 is a flange ring 23, and this ring finds a seat in a rotary ring 24 which is supported on the upper ends of a plurality of posts 25 the lower ends of which are secured in the cam plate 2. The carrier 21, though stationary, is thus supported on the rotary plate 2, and in turn supports the column 19 and, through the column, the superstructure 18. As previously set forth the post 12 depends from the fixed superstructure.

The upper portions of the slots 22 are occupied by jacks 28, said jacks being held in place by a coiled spring 29 which embraces the carrier and seats in registering recesses 31 in the outer edges of the walls of the said slots and in the upper ends of the jacks. The lower end of each of the jacks overlaps the upper end of a needle-wrapping finger 32 mounted in the lower end of the same slot, the said fingers being held in place by a coiled spring 33 which embraces the cylinder and seats in registering recesses 34 in the outer edges of the slot walls and in the fingers. Under actuation by the jacks 28 and associated mechanism hereinafter described, the fingers 32 serve in the present instance to wrap threads 35 drawn from bobbins 36 around the cylinder needles 8,

thereby to produce plating on the outside walls of the fabric formed by co-action of the said needles 8 with the dial needles 13. The bobbins 36 are mounted on platforms 37 secured to the column 19; and the manner in which the fingers 32, the lower ends of which are inclined to the radial planes containing the respectively associated cylinder needles, operate in the wrapping operation is shown in Fig. 10, wherein the lower end of one of the fingers is indicated by the reference numeral 38 and the upper end of the associated cylinder needle by the reference numeral 39. By reason of its inclination, the finger in its outward movement with respect to the cylinder is flexed to one side of the needle, and on its inward movement to the other side.

The manner in which the threads 35 pass to the fingers 32 is indicated in Fig. 2, wherein the threads after passing through eyelets (not shown) in the platform 37, are guided downwardly inside the ring 23 through the outer end of the jack slots on the carrier 21 and between the jacks and fingers to the lower ends of the latter.

The mechanism for operating the cylinder and dial needle cams is essentially the same as that disclosed in the aforesaid United States Patent 2,051,724. As shown in Fig. 1, the gear 17 meshes with a bevel gear 41 on a transverse shaft 42. The outer end of this shaft is hollow and serves as a guide for the foundation thread 43 through which the thread is fed to the cylinder and dial needles. The thread passes from the shaft 42 upwardly through an outlet tube 44 on the shaft. From the tube 44 the thread floats over arms 45 at the upper end of the stationary dial post 12 to an extension tube 46 on the upper end of a hollow post 47 which is one of two posts mounted on brackets 48 on the carrier support ring 24 and secured at their upper ends in a thread carrier ring 49, said ring 49 being guided between the periphery of a circular top plate 51 on the super structure 18, and a fixed annular stabilizing guide member 52 that is secured to the upper end of a standard 53 on bed plate 1. The thread 43 passes downwardly through post 47 and from the extended lower end thereof to the main thread guide which is secured to the cylinder cam ring 3 by a bracket 54.

The shaft 42 is journaled at the upper end of standard 53 and is connected through bevel gears 55 and 56 to a vertical shaft 57 which extends downwardly through the standard 53, the lower end of the shaft carrying a bevel gear 58. The gear 58 meshes with a bevel gear 59 on a horizontal shaft 61, and this shaft also carries a gear 62 which meshes with a gear 63 on shaft 64. As shown in Fig. 2, the gear 63 is connected by screws 65 to a gear element 66 and through this gear 66 the shaft 64 is connected, see Fig. 3, to a pinion 67 on the main operating shaft 68. To this shaft power is supplied by a pulley 69. The shaft 68 also carries a bevel pinion 71 which meshes with a ring gear 72 on the cylinder cam plate 2.

The shaft 68 is hollow, and supported therein is a second shaft 73 to which is attached a pulley 74 which closely adjoins the pulley 69. Loosely journaled on the end of shaft 73 is a third and idler pulley 75. The opposite end of the shaft 73 carries a pinion 76 which engages the gear 63.

Referring to Fig. 1, 77 is an intermittently operated pattern chain which rides on a sprocket 78

18, said sprocket being journaled on a fixed shaft 79 supported in the frame. In accordance with the principle disclosed in the aforesaid patent, this chain controls the operations of the 5 needle wrapping fingers 32 through the medium in the present instance of a pivoted lever 80. The yarn change pattern chain, controlling changes in the yarn 43 is shown at 82, this chain operating on a sprocket 83 fixed to a shaft 84 journaled in the frame. A lever 85, pivotally attached to the main frame at 86, carries a roller 87 which engages the chain 82, and the outer end of the lever 85 is connected through a link 88 to the yarn change device, indicated generally 15 by the reference numeral 89. Operatively associated with the sprocket 83 is a ratchet wheel 91 which is engaged by a pawl 92 mounted on an eccentric pin 93 at the end of the shaft 64.

Insofar as described, the operating mechanism 20 is essentially the same as that described in the aforesaid patent and forms no part of the present invention which is concerned primarily with the method of controlling and actuating the needle wrapping fingers 32. These fingers are 25 actuated in accordance with the principle disclosed in the aforesaid Patent No. 2,051,724, by means of a rotary cam 101 and 102 carried by the ring 24, the cam 101 being adjustable axially of the carrier 21 and co-acting with the 30 butts 103 of a longitudinal series on each of the said jacks. The butts are frangible and may be individually removed from the jacks to produce a desired pattern. The movements of the cam 101 longitudinally of the jacks and axially of the cylinder 21 are provided for by leaving out 35 of the cylinder 21 three adjoining jacks as indicated at Fig. 4 to leave a longitudinal space for the longitudinal travel of the cam. Rotary movement of the cam after adjustment will result in the cam contacting any of the butts of the jacks lying in its rotary path with the result that any of the jacks so contacted will be forced inwardly to rock the associated fingers 32 and to thereby effect by those fingers the thread wrapping operation on the cylinder needles 8 previously described. The cam 102 is fixed for engagement with the fingers 32 so that the fingers after rocking movement effected by the jacks 28 will be forced inwardly to the normal 40 position shown in Fig. 2. As shown in Fig. 4 the cam 101 leads the cam 102 and the present action of these two cams effect the rocking movement of the fingers required for the thread wrapping 45 operation.

The cam 101 is fixedly mounted in a head 104 which is slidably mounted on two posts 105 and 106 which are secured into and dependent upon the ring 24. As shown in Figs. 5 and 6 the post 106 is provided with a longitudinal series of notches 107 and the head 104 carries a pair of detents 108 and 109 which are mounted in cylindrical bores 111 and 112 in the head and are urged by springs 113 and 114 against the notched side of the post. The notches and the detents are relatively spaced so that when one of the detents engages one of the notches, the other detent will engage the post at a point half-way between two other adjoining notches, thus the detents are adapted to retain the post releasably in different positions spaced apart to the extent of one-half the distance between adjoining notches. This distance corresponds to the spacing of the frangible butts 103 on the jacks 28, thereby permitting the cam 101 carried by the head 104, to be indexed selectively

with any of the circumferential rows of butts axially of the carrier 21.

The cam 102 being secured to the lower ends of the posts 105 and 106 is stationary except for the rotary movement with the ring 24.

Carried by the sliding head 104 is a roller 115 and in operation this roller is adapted to coat with a guide member 116 which comprises two elements 117 and 118 best shown in Fig. 5. Spaced apart to an extent corresponding substantially to the diameter of the roller 115 each of the elements 117 and 118 has an angularly disposed lip 119 and 121 respectively, at one end which diverge with respect to each other to form a flared mouth. The member 116 is adapted to be positioned in the rotary path of the roller 115 as it moves with the ring 24 and the lips 119 and 121 function as cams to guide the roller into the normal space between the elements, as hereinafter described, and in this process to move the head 104 by camming action to a position of vertical adjustment on the rod 106 determined by the position of the guide member 116.

The guide member 116 is supported on the outer end of an arm 122 which projects laterally from a member 123. This latter member being slidably supported on a post 124 extending upwardly from the fixed frame of the machine. Adjustably secured to the member 123 is a rod 125 which carries an adjustable shoe 126 positioned for operative engagement with a roller 127 on the outer end of the lever 80, the arrangement being such that the position of the lever 81 as controlled by the pattern chain 77 controls the vertical position of the rod 125 and therefore of the member 123 and the guide member 116. The upper end of the rod 125 is threaded and the rod is rigidly secured to a bracket arm 128 on the member 123 through the medium of two nuts 129 and 131 which are tightened against opposite sides of the said arm as illustrated in Fig. 1. A bearing block 130 carried by the stationary post 24 slidably supports the rod 125 in vertical alignment therewith. This mode of attachment provides for vertical adjustment of the position of the rod 125 with respect to the slide member 123.

The lower end of the rod 125, see Fig. 7, is provided with a longitudinal series of teeth as indicated at 132 and operatively engaged with these teeth is a correspondingly toothed dog 134 on the end of a rod 135 slidably supported in the frame at 136 at one end thereof and in a depending bearing block 137 at the other. Intermediate its ends the rod 135 carries fixedly secured thereto an arm 138 which supports a guide pin 139 in axial alignment with the rod, said pin having sliding engagement in the bearing 137, the arrangement being such that while movement of the rod 135 longitudinally is permitted any rotation axially is prevented. The end of the rod 135 projecting beyond the bearing block 137 carries a cam roller 140 which coacts with a cam 141 on the side of the gear 63 as best shown in Fig. 8 and at each revolution of the gear 63 the cam 141 contacts the roller 140 and jogs the rod 135 to the left as viewed in Fig. 2 against the pressure of a spring 142 confined between the frame and a collar 143 on the rod. This movement of the rod 135, carrying with it the dog 134 is sufficient to free the dog from the teeth 132 of the rod 125 to thereby leave this rod free for vertical movement under actuation of the intermittently op-

erated pattern chain 77. It will be noted by reference to Fig. 7 that the dog 134 comprises a body member 144 secured to the end of the rod 135, said body member having mounted therein a pin 145 which is toothed at the side as indicated at 146 for engagement with the teeth 132 of the rod 125. It will be noted also by reference to Fig. 2 that the rod 125 is slidably supported in an arm 147 which extends laterally from the base 1 and which backs-up the rod 125 against the lateral strain of the spring 142 acting through the dog 134.

In operation the head 104 which carries the cam 101 rotates continuously with the ring 24. The rotation with the ring 24 is timed with the rotation of the gear 63 so that these two elements rotate at the same rate. As previously set forth each revolution of the gear 63 brings the cam 141 into engagement with the roller 140 to momentarily release the dog 134 from the rod 125. This momentary release is synchronized with the intermittent motion of the pattern chain 77 and in point of time is only of such duration as to permit the sprocket 78 to move a new link beneath the roller 81 of the lever 80. Thus, the varying height of the chain links as dictated by the pattern design, through the medium of the mechanism previously set forth and described, serve to adjust the vertical position of the guide 116 relative to the head 104 and the roller 115 carried thereby. This selective positioning of the guide 116 during a single relative revolution of the head 104 and carrier 21, may occur at any time after the roller 115 leaves the guide 116 and before it re-enters again near the completion of the revolution. However, during the interval when the roller 115 is coactive with the guide 116 the dog 134 will function to hold the rod 125 rigidly in the adjusted position securing the head 104 against any possible displacement vertically on the shaft 124. This locking-in of the head 104 and associated cams 101 and 102 excepting for the relatively short time interval when response to a pattern change is indicated, insures a positive control of the positioning mechanism particularly when operating in the higher speed range.

It will be obvious that when the plated design formation is repeated in successive courses during the knitting the guide 116 will be retained in the same position of elevation for the necessary number of revolutions of the head 104 and is supported immobilized on the posts 105, 106 by the detent 108 or 109, as the case may be, during the intervals when the dog 134 effects release of the rod 125.

Assuming that the guide member 116 has been readjusted to a new position at some point during one revolution of the ring 24 and cam 101, the roller 115 will then by reason of the subject contact one or another of the lips 119 and 121 and by camming action of the lip will force the head 104 to a new position in which the cam 101 will engage another circumferential series of butts on the jacks 28. The guide 116 is so positioned with respect to the vertical space on the carrier 21 from which the jacks have been removed that the adjustment of the head 104 occurs during the period that the cam 101 is traversing this space as that the cam is free to move axially of the latter. It should be noted that this expedient is only made necessary when the design being worked covers the entire stocking top circumferentially. More

often, however, the plated figuring, i. e., that part of the pattern controlled by the wrapping fingers 32, is sufficiently spaced apart at the points where the design is repeated as to permit ample space for axial traverse of the head 104 with respect to the carrier 21. It being understood, of course, that at such points the jacks and associated fingers would be deleted from the carrier slots 22.

In Fig. 9 the cam 101 is shown in an intermediate position of adjustment relative to the jacks 28, the broken line positions 101a and 101b indicating the extremes of the effective operational range, the number of possible pattern changes being limited only by the number of frangible butts 103 carried by the individual jacks 28. The neutral or home position is indicated at 101c.

While it may be desirable to employ a greater number or all of the butts in working a particular design, for most work it has been found that comparatively few, perhaps six or eight, are ample. In the case of the latter, a plurality of different patterns may be set up on the same jacks making it necessary when switching from one run of pattern to another to merely substitute the corresponding pattern chain. The single mechanical adjustment necessary would be to simply loosen the nuts 129 and 131 on the rod 125 and adjust the head bracket 128 so that the cam 101 would be made to cooperate with the proper series of butts 103. In any case the adjustment of the cam would be to a home or neutral position of the particular series, which would be made by removing a circumferential row of butts between adjacent pattern series.

Fig. 11 illustrates schematically a stocking top made according to the practice of the invention. Being a ribbed knit fabric, the dial wales are considered as not showing, the fabric presumed to be in a relaxed condition. Consequently, adjacent cylinder wales carrying the plated or vertical stripes of the design are shown abutting, presenting an unbroken outline circumferentially of the top when utilized in figuring or striping. The reference character P is used to identify the plated portion of the design, all other parts thereof being part of the base fabric which is under control of the striping attachment. This latter control is well described in the aforementioned Patent No. 2,051,724, suffice it to say here that the yarn change mechanism described earlier and indicated at 89 is actuated by the varying height of the component links of the pattern chain 82, after the manner of the chain 77.

Having set forth and described my invention and the practice of the same as applicable to designs for stocking tops, it will be obvious to those skilled in the art that its use is equally applicable in the production of any other form of tubular ribbed fabric.

I claim:

1. The combination in a circular rib knitting machine, of a needle cylinder, a needle dial, needles in the cylinder and dial respectively, a cylindrical carrier above the dial, a plurality of thread-manipulating fingers supported by the carrier in operative relation to said needles, and

means for selectively actuating said fingers, said means comprising a selector cam support member movable in a circular path around the carrier, adjustable guide means positioned in the path of said member for adjusting the latter to selected positions axially of the carrier, mechanism for adjusting the guide means axially of the carrier, means normally operative to lock the guide means in adjusted position, and means operating in synchronism with the guide means adjusting mechanism for momentarily releasing the locking means to permit said adjustments.

10 2. A knitting machine according to claim 1 wherein the guide means adjusting mechanism includes a pattern chain operating in synchronism with the said release means.

20 3. A knitting machine according to claim 1 wherein the selector cam supporting member is slidably supported upon rods extending axially of the finger carrier, one of said rods being toothed to form a rack, and said member having a spring pressed detent for engagement with the rack.

25 4. A knitting machine according to claim 1 wherein the said member carries a follower element for camming engagement with the guide means.

30 5. A knitting machine according to claim 4 wherein the said guide means is in the form of spaced rails having divergent lips to direct the said follower element of the selector cam supporting member to the space between the rails.

6. A knitting machine according to claim 5 wherein the said follower element closely fits the space between the rails.

35 7. A knitting machine according to claim 1 including a rotary cylinder cam plate and means for connecting the selector cam support member to said plate for rotation with the latter.

8. A knitting machine according to claim 7 wherein the guide lock means is operatively connected with the said cam plate for operation in synchronism with the rotary movement of the plate.

45 9. A knitting machine according to claim 8 wherein the guide lock means comprises a rack movable with the guide means, a spring pressed detent normally engaging said rack, and means operating in synchronism with the cam plate for intermittently releasing said detent from the rack.

50 10. A knitting machine according to claim 9 wherein the rack is adjustable with respect to the guide means in a direction parallel to the axis of the finger carrier.

55 WALTER LARKIN.
